HERKEN HIERONYMUS HERKENS, OF GILMAN, ILLINOIS.

FORK-CLAMP.

1,246,597.

Specification of Letters Patent. Patented Nov. 13, 1917.

Application filed July 27, 1916. Serial No. 111,701.

To all whom it may concern:

Be it known that I, HERKEN H. HERKENS, a citizen of the United States, residing at Gilman, in the county of Iroquois and State 5 of Illinois, have invented a new and useful Fork-Clamp, of which the following is a specification.

The present invention relates to a clamp for application to forks, and the like.

10 The object of the present invention is to provide a clamp, which may be quickly and easily applied to forks to hold the same rigidly upon their handles, when the handle is dried out and becomes loose.

15 The above object is accomplished by the provision of a clamp in the form of a strap adapted to encircle the handle and having a tongue for engagement around the head of the fork to hold it firmly to the handle, 20 the free end of the tongue being clamped beneath the strap against the handle when the clamp is in position.

25 The invention will be best understood from a consideration of the following detailed description, taken in connection with the accompanying drawing forming part of this specification, with the further understanding that while the drawing shows a practical form of the invention the latter is 30 not confined to strict conformity with the showing of the drawing, but may be changed and modified so long as such changes and modifications come within the scope of the appended claims.

35 In the drawing:—

Figure 1 is a front elevation of a fork, the handle and the lower ends of the prongs or tines being broken away, and showing a clamp, constructed according to the present 40 invention, applied to the fork.

Fig. 2 is an enlarged section, taken longitudinally on the line 2—2 of Fig. 1, showing the tongue secured beneath the strap or clamp.

45 Fig. 3 is a transverse section, taken on the line 3—3 of Fig. 2, showing the position of the strap when tightened.

Fig. 4 is a transverse section taken on the line 4—4 of Fig. 2, showing the location of 50 the tongue when applied.

Fig. 5 is a plan view of the blank from which the improved clamp is formed.

Fig. 6 is a rear elevation of a slightly different type of fork, showing the improved 55 clamp applied thereto.

Referring to the drawing, wherein like

parts are designated by similar numerals of reference throughout the several views, 10 designates the ordinary wooden handle of a fork. As best shown in Fig. 2, the handle 60 is incased at its lower end in a ferrule 11, which latter is reinforced and strengthened by a thimble 12, engaging about the lower end of the ferrule, and being suitably slotted to receive therethrough the transversely extending head 13 of the fork. A shank 14 projects from the head 13 into the handle 10. The head 13 is provided in the usual manner with tines or prongs 15 in any suitable number, and of the usual form. 65

Frequently, the handle 10 dries out and the head of the fork becomes loose, and frequently becomes detached. To overcome these difficulties, the present invention provides a strap 16 of flexible metal such as zinc 70 sheeting adapted to encircle the ferrule 11, and has its opposite ends apertured and turned outwardly to provide supporting lips for a clamping bolt 17, which is passed through the lips and tightened to contract 75 the strap 16 about the ferrule above the thimble. From Fig. 2, particularly, it will be noted that the upper end of the thimble 12, which terminates a short distance above the lower end of the ferrule 11, provides an 80 annular abrupt shoulder 18 against which the strap 16 may engage when the strap is secured about the ferrule whereby it is securely held on the handle and will not slip off. 85

The strap 16 is provided with a preferably integral tongue 19 of like material, which extends from one long edge of the strap, and is adapted to be looped from one side of the thimble 12 about the fork head 13, and to be 90 carried from the latter against the opposite side of the thimble. 95

The tongue has, intermediate its ends, a longitudinal slot 20 adapted to receive one prong 15 of the fork, and the slot is of sufficient length to permit adjustment of the clamp to forks of different sizes. The free end of the tongue is adapted to be lodged between the strap 16 and the ferrule 11 with the extremity of the tongue projecting 100 beyond the strap. When the strap 16 is tightened, the end of the tongue 19 is bound against the ferrule 11, and the portions thereof over the shoulder 18 are offset, as shown in Fig. 2, to hold the strap in place 110 and to prevent the free end of the tongue from pulling out of the strap. If desired,

the free projecting extremity of the tongue 19 may be overturned upon the strap 16, as shown.

In Fig. 6, the clamp is disclosed as applied to a different type of fork, or that type of fork, wherein there is no central tine, so that the tongue 19 is merely wrapped around the middle portion of the head 13^a. The tines or prongs 15^a are arranged in 10 suitably spaced apart relation at the opposite sides of the tongue 19.

The tongue 19 may be formed upon the strap 16 near one end of the latter, as shown in Fig. 5, so that when the clamping screw 17 is in place, the same will lie at one side of the fork out of the way.

What is claimed is:—

1. A blank for a fork clamp comprising an elongated body portion providing a strap adapted to be bent about and to encircle the handle of a fork and having means at its terminals for binding the strap upon the handle, the blank also having an elongated portion projecting from one edge of said body portion at an angle thereto, and of a length sufficient to be looped about the head of a fork and engaged at its free end with the body portion and held in place thereby.

2. The combination with a fork having a handle, and a thimble upon one end of the handle providing an abrupt shoulder about the handle, of a strap encircling the handle above said shoulder, a tongue on the strap 35 at one side of the handle adapted to be looped about the head of the fork, and returned against the opposite side of said handle with its free end between the latter and said strap, whereby upon the tightening 40 of the strap the tongue is clamped against the opposite sides of said handle, and is offset over the shoulder to secure the tongue in place.

3. A blank for a fork clamp comprising 45 an elongated body portion providing a strap adapted to be bent about and to encircle the handle of a fork and having openings in its terminals to receive a clamping bolt to bind the strap upon the handle, the blank also

having an elongated portion projecting from 50 one edge and intermediate the ends of said body portion providing a tongue of a length sufficient to be looped about the head of the fork and to be clamped at its free end between the strap and the handle.

4. A blank for a fork clamp comprising an elongated body portion providing a strap adapted to be engaged about the handle of a fork and having apertures in its opposite terminals for the reception of a clamping 60 bolt to bind the strap on the handle, the blank also having an elongated projecting portion at one edge and intermediate the ends of said body portion providing a tongue adapted to be looped about the head of the 65 fork, said tongue being provided with an opening intermediate its ends to receive therethrough the middle tine of a fork when present, said tongue being of a length to engage about the head of the fork and project 70 at its free end between the handle and the strap to secure the tongue in place when the strap is tightened.

5. A fork clamp comprising a body portion in the form of a strap adapted to encircle a handle, and a tongue connected with the body portion and extending from one side of the same and adapted to be looped about the head of a fork, the free end of the tongue being passed through the body 80 portion and hooked around one edge of the same.

6. In combination with a fork and a handle, the latter having a shoulder at one end, a strap encircling the handle above 85 the shoulder, means for connecting the ends of the strap, and a tongue leading from one side of the strap at an angle thereto and of a length sufficient to be looped about the head of the fork, and have its free end connected to the strap and held in place thereby.

In testimony that I claim the foregoing as my own, I have hereto affixed my signature in the presence of two witnesses.

HERKEN HIERONYMUS HERKENS.
